DRAFT-GEAR.

1,243,085.

Specification of Letters Patent. Patented Oct. 16, 1917.

Application filed July 10, 1916. Serial No. 108,810.

To all whom it may concern:

Be it known that we, ROBERT L. MCINTOSH and RALPH G. TAYLOR, citizens of the United States, residing at Wilmette, county of Cook, and State of Illinois, and Chicago, county of Cook, and State of Illinois, respectively, have invented certain new and useful Improvements in Draft-Gears, of which the following is a specification.

10 Our invention pertains to features of novelty and improvement in railway-car draft-gear and relates more particularly to draft appliances of the friction type employing one or more wedges. One of the prominent 15 features of the invention resides in the simplicity of the structure and its effectiveness in operation.

In its preferred embodiment the invention comprises a hollow casing or housing bearing against one set of the draft-sill stops or 20 abutments and coacting with the inner surfaces of the opposite side-walls of such member are a pair of beveled pressure-blocks which, during their sliding travel on the 25 housing, are pressed thereagainst by the action of a pair of wedges co-operating through a follower with the other set of draft-sill stops and forced outwardly as they move relatively to the housing by an interposed 30 beveled post or spreader, desirably, but not necessarily, integral with the housing. The inner ends of the pressure-blocks are maintained in adequate frictional engagement with the housing walls during their travel 35 and their inward movement is resisted by one or more springs arranged longitudinally of the casing, bearing at one end against the latter and pressing at the other end against a cap-member whose beveled faces engage 40 the correspondingly-shaped surfaces of the pressure-blocks.

It will be appreciated, therefore, that one of the salient objects of the invention is the provision of a simple device which will force 45 the blocks outwardly in opposite directions against the housing, at the same time permitting them to slide thereon. A further feature of the invention is the production of a variable or differential travel of the various elements to produce the required friction.

In order that those skilled in the art may have a clear understanding of the structural and functional advantages of a draft-gear

appliance embodying this invention, a desirable construction incorporating the invention has been illustrated in the accompanying drawings forming a part of this specification and throughout the various views of which like reference characters refer to the same parts.

In the drawing:

Figure 1 is a horizontal section through the draft-gear;

Fig. 2 is a similar view, parts being shown 65 in plan and with the gear partly compressed; and

Fig. 3 is a central longitudinal vertical section on line 3—3 of Fig. 1, with the coupler-shank and its yoke omitted. 70

The appliance includes the usual draft-sills 10, 10, and the opposed stops 11, 11, and 12, 12. A follower 13 co-acts with stops or abutments 12, 12, and the shank 14 of the coupler, the yoke 15 of the latter being 75 looped around a housing or casing characterized as a whole as 16, but composed of two parts or sections 17 and 18, of which the rearmost one, 18, co-operates with the stops 11, 11, and with the yoke. This part 80 or section 18 is cylindrical in form, its interior accommodating the rear portions of the nested compression springs 19 and 20 which bear at their ends against the terminal wall 21 of the part 18 with which wall the yoke 85 also co-acts. Externally, the shell 18 at each end has oppositely-extended transverse wings 22 and 23, the former functioning with the stops 11 and 11, the latter affording convenient means for attachment to the 90 front shell or housing 17. In order to strengthen this rear, hollow casting, it is equipped with longitudinal ribs 24 connecting and bracing the wings 22 and 23. 95

The forward part of shell 17 is rectangular in vertical cross-section and has a flat bottom-wall or floor 25, vertical side-walls 26 and 27, and a top-wall 28. Its rear portion 29, however, is cylindrical in cross-section matching the element 18, and its outwardly-extended wings 30 bear against and are secured rigidly to the wings 23 by bolts 31. Outstanding stiffening and strengthening ribs 33 connect wings 30 with offsets or shoulders 32 of the casting. 100 105

Cast integral with the housing 17 at the middle or center of its front end, and extending between and connecting its top and

bottom walls, is a vertical-wedge or beveled-spreader 34 having diverging walls 35 and 36 co-acting with the inner diverging faces 37 and 38 of two hollow wedge-blocks 39 and 40, preferably equilateral in horizontal cross-section, substantially equal in height to the corresponding dimension of the space in the housing, and supported and sliding on the floor 25. The front flat faces 41 and 42 of the wedge-blocks bear against and are adapted to travel laterally on the rear surface of follower 13.

The remaining faces 43 and 44 of these blocks coöperate with beveled surfaces 45 of a pair of hollow pressure-blocks or members 46 and 47 each having a plane face 48 pressing against and adapted to slide on the inner surface of the corresponding housing side-wall 26 or 27, as the case may be. The floor 20 or bottom-wall of the housing or casing also supports these pressure-blocks, as will be seen from the drawings. It will be clear, therefore, that the wedges 39 and 40 are interposed between the central separator or 25 wedge 34 and the two oppositely-disposed pressure-members 46 and 47.

These sliding blocks 46 and 47 are desirably symmetrical in shape, among other reasons, to prevent possibility of improper assembly with the companion elements, that is to say, each block has an inner beveled surface 49, the two of which are acted upon by the opposite, similarly-beveled ends 50 and 51 of a spring-cap 52 of the form in cross-section indicated in Figs. 1 and 2 and against which the outer ends of the springs press.

The operation of the appliance occurs practically as follows:

40 Under buffing strains the coupler-shank 14 carries the follower 13 inwardly away from the front stops 12, 12, the yoke also traveling rearwardly leaving the duplex or compound housing 16 in engagement with 45 the back-stops 11, 11. As follower 13 moves inwardly the pair of wedge blocks 39 and 40 are forced in the same direction, and, by reason of the presence of the stationary wedge or beveled spreader 34, they are, at 50 the same time, spread apart or separated, that is, they travel outwardly laterally of the appliance in opposite directions, sliding on the follower. Such compound motion of the wedges forces the pressure-blocks 46 and 55 47 longitudinally inwardly or rearwardly of the structure and also transversely outwardly against the housing side-walls. Of course, such movements of the parts pushes back the beveled cap 52 against the action 60 of springs 19 and 20, the sloping ends of the cap holding the inner ends of the pressure-blocks out against the housing walls. It should be noted that shock-absorbing friction is present between the wedges 39 and 65 40 and the follower 13, between such wedges

and the fixed beveled separator or wedge 34, between the wedges and the pressure-blocks 46 and 47 and between the latter and the housing side-walls. The springs obviously oppose the inward travel of these parts and maintain the inner ends of the pressure-blocks against moving inwardly away from the housing walls. It should be observed, furthermore, that the pressure-blocks and the spring-cap travel twice as rapidly and twice as far longitudinally of the structure as the wedges do because of the 60° relation between the surfaces of the coöperating elements or, stated differently, there is a differential movement between some of the friction parts of the appliance, thus securing the required shock-dissipating friction.

By those skilled in this art it will be appreciated that by employing a central wedge fixed relatively to the housing or casing and by using the associated wedges, a suitable lateral pressure is obtained on both of the pressure-blocks, thus securing the needed friction during their sliding action on the housing-walls.

When a pull instead of a buff is imposed on the coupler the follower 13 remains in contact with the stops 12, 12, and the yoke causes the housing to travel forwardly away from the abutments 11, 11. Under these circumstances the wedges 39 and 40 do not move longitudinally of the appliance, but merely separate, traveling laterally outwardly, sliding, as will be clear, on the face of the follower. This movement is occasioned by the entering action of the wedge 34 between these two equilateral wedges. The outward movement of the latter causes an inward axial movement of the pressure-blocks, so that we have the housing traveling in one direction and the pressure-blocks moving in the opposite direction, thus obtaining the desired differential travel of the friction elements of the appliance and securing the needed friction at the points indicated. The movement of the blocks 46 and 47 carries the spring-cap 52 in the same direction so that under these circumstances the spring 19 and 20 are compressed from both ends. In the two instances cited the relative movements of the friction elements are substantially the same, the parts functioning in practically the same manner under both conditions.

The housing or inclosing casing is made in two parts or sections as described to permit the introduction of the springs, after which insertion the parts are bolted together.

While we have herein presented pictorially and by description a preferred and desirable embodiment of the invention, it is to be understood that the latter is not limited and restricted to the precise and exact details of structure, because these may be modified and changed in many respects without

departure from the substance of the invention and without sacrificing any of its substantial benefits and advantages.

We claim:

5. 1. In a cushioning appliance of the character described adapted for railway-car draft-gear and other uses, the combination of a housing, a member rigid with said housing, a pressure-block adapted to slide 10 on a wall of said housing, a spring in said housing opposing the travel of said block relatively to said housing, and a wedge interposed between and in sliding contact with said member and pressure-block, substantially 15 as described.

2. In a cushioning appliance of the character described adapted for railway-car draft-gear and other uses, the combination of a housing adapted to coöperate with a 20 stop or stops, a follower to co-act with the opposed stop or stops, a member rigid with said housing, a pressure-block adapted to slide on a wall of said housing, a spring in said housing opposing the travel of said 25 block relatively to said housing, and a wedge interposed between and in sliding contact with said member and pressure-block, and adapted to coöperate with and travel transversely of the appliance on said follower, 30 substantially as described.

3. In a cushioning appliance of the character described adapted for railway-car draft-gear and other uses, the combination of a housing, a beveled member rigid with 35 said housing, a beveled pressure-block adapted to slide on a wall of said housing, a spring in said housing opposing the travel of said block relatively to said housing, and a wedge interposed between and in sliding contact 40 with the beveled faces of said member and pressure-block, substantially as described.

4. In a cushioning appliance of the character described adapted for railway-car draft-gear and other uses, the combination 45 of a housing, adapted to coöperate with a stop or stops, a follower to co-act with the opposed stop or stops, a beveled member rigid with said housing, a beveled pressure-block adapted to slide on the wall of said 50 housing, a spring in and disposed longitudinally of said housing opposing the travel of said block relatively to said housing, and a wedge interposed between and in sliding

contact with the beveled faces of said member and pressure-block, and adapted to co- 55 operate with and travel transversely of the appliance on said follower, substantially as described.

5. In a cushioning appliance of the character described adapted for railroad-car 60 draft-gear and other uses, the combination of a housing, a member rigid with said housing, a pair of pressure-blocks adapted to slide on opposite interior walls of said housing, a spring in said housing opposing 65 the travel of the pressure-blocks relatively to the housing, and a pair of wedges interposed between and in sliding contact with said member and said pressure-blocks, substantially as described. 70

6. In a cushioning appliance of the character described adapted for railway-car draft-gear and other uses, the combination of a housing to coöperate with a stop or 75 stops, a follower to co-act with the opposed stop or stops, a member rigid with said housing, a pair of pressure-blocks adapted to slide on opposite walls of said housing, a spring in said housing opposing the travel of said pressure-blocks relatively to said 80 housing, and a pair of wedges interposed between and in sliding contact with said member and said pressure-blocks and adapted to travel transversely of the appliance on said follower, substantially as described. 85

7. In a cushioning appliance of the character described adapted for railway-car draft-gear and other uses, the combination of a housing adapted to coöperate with a stop or stops, a follower adapted to co-act with the opposed stop or stops, an oppositely beveled member rigid with said housing, a pair of beveled pressure-blocks adapted to slide on opposite walls of said housing, a spring in and disposed longitudinally of 95 said housing opposing the travel of said pressure-blocks relatively to said housing, and a pair of wedges interposed between and in sliding contact with the beveled faces of said member and pressure-blocks and 100 adapted to coöperate with and travel transversely of the appliance on said follower, substantially as described.
